(57) **CLAIM**

The ornamental design for a hair parting tool, as shown and described.

DESCRIPTION

FIG. 1 is an isometric view showing a first embodiment of a hair parting tool according to the present disclosure; FIG. 2 is another isometric view of the hair parting tool shown in FIG. 1;

FIG. 3 is a front elevational view of the hair parting tool shown in FIG. 1;

FIG. 4 is a right side elevational view of the hair parting tool shown in FIG. 1;

FIG. 5 is a rear elevational view of the hair parting tool shown in FIG. 1;

FIG. 6 is a left side elevational view of the hair parting tool shown in FIG. 1;

FIG. 7 is a top plan view of the hair parting tool shown in FIG. 1;

FIG. 8 is a bottom plan view of the hair parting tool shown in FIG. 1;

FIG. 9 is an isometric view showing a second embodiment of the hair parting tool according to the present disclosure; FIG. 10 is another isometric view of the hair parting tool shown in FIG. 9;

FIG. 11 is a front elevational view of the hair parting tool shown in FIG. 9;

FIG. 12 is a right side elevational view of the hair parting tool shown in FIG. 9;

FIG. 13 is a rear elevational view of the hair parting tool shown in FIG. 9;

FIG. 14 is a left side elevational view of the hair parting tool shown in FIG. 9;

FIG. 15 is a top plan view of the hair parting tool shown in FIG. 9; and,

FIG. 16 is a bottom plan view of the hair parting tool shown in FIG. 9.

(Continued)

The broken lines in the figures represent portions of the hair parting tool that form no part of the claimed design.
